UNITED STATES PATENT OFFICE.

MAURICE J. WOHL AND HARRY HERTZBERG, OF NEW YORK, N. Y., ASSIGNORS TO M. J. WOHL AND COMPANY, INC., A CORPORATION OF NEW YORK.

ARC-LAMP.

1,394,876.

Specification of Letters Patent.

Patented Oct. 25, 1921.

Application filed June 14, 1918. Serial No. 239,947.

To all whom it may concern:

Be it known that MAURICE J. WOHL and HARRY HERTZBERG, citizens of the United States, and residents of Brooklyn, county 5 of Kings, city and State of New York, have invented certain new and useful Improvements in Arc-Lamps, of which the following is a specification.

This invention relates to electric arc lamps, 10 the arrangement being designed more particularly for arc lamps used in motion picture photography, although not limited to such use.

The invention has for a general object the 15 provision of a simple and efficiently acting arc lamp in which the carbons are laterally offset from the control mechanism.

More specifically, the invention has for an object to provide an improved arrangement and construction of the support or 20 mounting for the movable carbon, whereby the support is maintained in rolling contact with its guides and carries the carbons in an offset position.

For further comprehension of the invention and of the objects and advantages thereof, reference will be had to the following 25 description and accompanying drawings describing and illustrating one embodiment of the invention, and to the appended claims in which the novel features of the invention are set forth.

Figure 1 of the drawings is a side elevation of an arc lamp embodying the invention.

Fig. 2 is a horizontal section on the line 2—2 of Fig. 1.

Fig. 3 is a fragmentary vertical section on the line 3—3 of Fig. 1.

Fig. 4 is an enlarged detail horizontal section on the line 4—4 of Fig. 3.

As here shown, the frame of my improved arc lamp comprises the top and bottom castings 1 and 2, and an intermediate plate 3. 45 The plate 3 is rigidly connected to the bottom casting 2 by the vertical posts 4 located at the corners of the frame. The plate 3 is also rigidly connected to the top casting 1 by the vertical posts 5, which are equally 50 spaced in pairs on opposite sides of the median line of the lamp, as shown in Fig. 2; these posts 5 serving also as guides for

the carbon carrier, as will be presently pointed out.

Carried by the top casting 1 is a solenoid 6, which may be secured in position by any suitable means. The core 7 of the solenoid is connected to a dash pot 9 through a resilient yoke 10, the dash pot being supported on a horizontal bar 11 carried by the vertical rods 12, which are attached at their upper ends to the casting 1. The resilient yoke 10 carries a cross bar 13 to which are connected the upper ends of the rods 14 having clutches 15 of usual type attached to their lower ends. The mounting of the solenoid 6 and dash pot 9 and the construction and connection of the resilient yoke 10, cross bar 13 and rods 14 may all be arranged as shown and described in a previous Patent No. 1,235,271, issued to Maurice J. Wohl, one of the applicants herein, on July 31, 1917. Further description of these parts is, therefore, not given here.

The clutches 15 engage vertical rods 16, which are located between the respective pairs of the posts 5, and are longitudinally adjustable. These rods are rigidly secured at their upper ends, as by the nuts 17, to brackets 18 to which are fixed the lateral arms 19 carrying the upper carbon holders 20, the arms 19 being insulated from the brackets 18, as indicated at 21. The arms 19 extend in a direction to position the corresponding carbon holder and posts in a common plane, as will be apparent from Fig. 2. Carried by the brackets 18 between the pairs of posts 5 are the pivoted rollers 22 which are slightly smaller in diameter than the distance between the respective posts of each pair.

As shown most clearly in Fig. 2, the brackets 18 extend along the posts 5 on one side thereof and are provided with supplementary strips 18^a which extend along the opposite sides of the posts, thus preventing lateral displacement of the rollers 22.

The rods 16 extend downwardly through suitable apertures in the plate 3 into tubes 23, fixed to the plate 3 at their upper ends and which may extend through the bottom casting 2 at their lower ends, as shown in Fig. 3. Pivoted in the lower end of each of the rods 16 is a pair of rollers, 24 and

25, arranged one above the other and at right angles to one another, as clearly shown in Figs. 3 and 4, the diameter of these rollers being slightly less than the interior diameter 5 of the tubes.

The holders 26 for the fixed carbons may be carried by lateral arms 27 secured to and insulated from depending lugs 28 formed integral with the plate 3. While only one of 10 these holders for the fixed carbon is shown in the drawings, it will be obvious that there will be one in vertical alinement with each of the carbon holders 20.

It is not considered necessary to illustrate 15 the electrical connections, which may be through the solenoid, down one pair of carbons, through the resistances (indicated at 29 as depending from the plate 3) and up through the other pair of carbons, the insulated arms 27 forming the medium for 20 connection to the carbons.

The arrangement of laterally offset carbons serve various purposes and have several advantages in arc lamp construction. 25 In the present instance they provide for the use of the reflector, indicated in dotted lines at 30 in Fig. 1, which may be secured in place in any suitable manner and provided with the necessary vertical slots to accommodate 30 the carbon mountings.

With the arrangement here shown all danger of the movable carbon support failing to operate properly, by reason of its support binding or sticking is eliminated. 35 As shown clearly in the drawings, the rollers 22, their guiding posts 5, the arms 19, carbon holders 20 and rollers 24 and 25 all extend in one general plane so that the lateral pressure is taken up directly by the 40 rollers 22 and 25. By this arrangement any tendency of the clutches to pull the dummy carbons in a direction at right angles to the plane above referred to and to cause the supports to bind or stick is overcome and the 45 carbon supports are maintained in rolling contact with the guides. This not only insures a more efficient operation of the lamp mechanism but results in a steady light and absence of flicker. Also the arc adjusts itself 50 quickly to changing conditions, both in starting and while in operation, and per-

mits of satisfactory operation of lamps when tested.

What we claim is:—

1. In an arc lamp, the combination with 55 control mechanism including a clutch, of a carbon rod engaged by said clutch, a pair of posts disposed on opposite sides of said dummy carbon, a tube into which said carbon rod extends at its lower end, a bracket 60 to which the carbon rod is attached at its upper end, an arm extending from said bracket substantially in a common plane with the said posts; a carbon holder carried by the said arm, and means for maintaining 65 supports for the carbon rod in rolling contact with said posts and the interior of the said tube.

2. In an arc lamp, the combination with control mechanism including a clutch, of a 70 carbon rod engaged by said clutch, a pair of guide members for the upper end of said carbon rod disposed on opposite sides thereof, a roller carried by the upper end of the carbon rod between the said guides, a pair 75 of rollers carried by the lower end of the carbon rod and having their axes at right angles to one another, and a guide for the lower end of the carbon rod having guiding faces positioned and adapted to be engaged 80 by said rollers.

3. In an arc lamp, the combination with control mechanism including a clutch, of a carbon rod engaged by said clutch, a pair of posts located on opposite sides of said 85 carbon rod, a bracket to which the upper end of said carbon rod is attached, an arm extending from said bracket substantially in a common plane with the said posts; a carbon holder carried by said arm, a roller pivoted to said bracket and positioned between the said posts, a tube into which said carbon rod extends at its lower end, and a pair of rollers pivotally carried by the lower end of said carbon rod and having their axes at 90 95 right angles to one another.

Signed at Brooklyn, county of Kings, city and State of New York, this 31 day of May, 1918.

MAURICE J. WOHL.
HARRY HERTZBERG.
